FOLDING BRACKET SHELF

John G. L. Skar, Jamestown, N. Y., assignor to
Art Metal Construction Company, Jamestown,
N. Y., a corporation of New York

Application March 15, 1950, Serial No. 149,750

2 Claims. (CL 211—149)

1

This invention relates to bracket shelves made of sheet metal such as are employed in library bookstacks of the type in which the shelves are mounted on upright metal columns by vertical end brackets hinged to each end of each shelf and which serve as end walls for each shelf and are detachably or adjustably connected to the upright columns.

One of the principal objects of the present invention is to provide a simple and inexpensive hinge connection for permanently connecting each shelf to its companion pair of end brackets and which permits these brackets to be folded from their perpendicular or vertical shelf supporting position to a position close alongside the shelf for economizing space in storage or shipping and which at all times prevents the brackets from being detached from the shelves and lost or mislaid.

Another object is to provide such a hinge connection which does not require any added metal for the shelf or brackets, the hinge parts being shaped out of the sides of the brackets and the necessary end flanges of the shelf.

Another object is to provide such a hinge which is strong and durable in construction and will function without binding or distortion under severe service conditions.

Another object is to provide such a hinge which can be formed and assembled with simple tools and operations.

Other objects and advantages of the invention will appear from the following description and drawings, in which:

Fig. 1 is a fragmentary front elevational view, on a reduced scale, of a metal library bookstack or shelving structure having bracket shelves embodying the present invention.

Fig. 2 is an end elevational view of a shelf unit embodying the present invention and showing the supporting column in section, this view being on an enlarged scale.

Fig. 3 is a further enlarged fragmentary perspective view of one part of a shelf showing the manner in which it is formed to provide a hinge leaf of the hinge connection.

Fig. 4 is a companion fragmentary perspective view of a part of the bracket and showing the manner in which the same is apertured to receive the hinge leaf shown in Fig. 3 and the manner in which it is provided with a tang to hold the hinge parts in permanently assembled relation.

Fig. 5 is a perspective view similar to Figs. 3 and 4 and showing the shelf and end bracket and

2

their hinge parts assembled and the tang straightened so as to hold the parts of the hinge permanently in position.

Fig. 6 is a fragmentary vertical sectional view taken on line 6—6 and showing the hinge connection before the tang has been straightened to hold the hinge parts interlocked.

Fig. 7 is a view similar to Fig. 6 showing the tang after it has been straightened to hold the hinge parts interlocked.

Fig. 8 is a view similar to Fig. 7 and showing the end bracket swung down to its collapsed position in which it is disposed on top of the shelf and parallel therewith.

15 The library bookstacks to which the present invention is applied are shown as composed of a plurality of metal shelves, indicated generally at 10, each having a pair of brackets 11 hinged to its opposite ends, and these brackets being supported by upright columns 12, which are shown as being of square tubular form and each provided along its front side with two vertical series of vertical slots 13.

20 Each of the shelves 10 is made of sheet metal and is shown as reinforced along its opposite longitudinal edges by a bead 14 which can be conveniently formed by providing a depending reversely formed or C-shaped flange along the corresponding longitudinal edge of the shelf.

25 At its opposite ends each shelf is provided with a depending flange 15 which preferably projects downwardly a distance equal to the downward extension of the longitudinal beads 14.

30 Each end bracket 11 is made of sheet metal and is generally rectangular form with its outer upper corner preferably rounded, as indicated at 16, and this rounded part 16 and the front and upper edges of the bracket preferably being formed to provide a rounding outwardly projecting head or shallow flange 18. Each bracket

35 is also provided along the upper part of its rear edge with a pair of downwardly directed hooks 19 and which are adapted to enter a corresponding pair of the vertical slots 13 of the supporting column 12 and hold the bracket against forward displacement. Each bracket 11 is also provided along the lower part of its rear edge with a rearwardly projecting square lug or extension 20

40 which is adapted to enter a lower slot 13 of the series supporting the hooks 19 and hold the lower part of the end bracket against sidewise displacement. Each bracket 11 is also provided along its lower edge with an inwardly projecting horizontal flange 21 on which the corresponding end

45

flange 15 of its shelf 10 rests, as best shown in Figs. 6 and 7.

The invention is essentially directed to the hinge connection between each of the end brackets 11 and its shelf 10 whereby these parts are permanently joined together but which permits the brackets 11 to be folded down upon the shelf 10 from the vertical position shown in Figs. 1-7 to the horizontal position shown in Fig. 8. Each end bracket 11 is secured to the corresponding end of its companion shelf 10 by a pair of such hinges and which are indicated generally at 22.

Each of the hinges 22 is formed in part by a leaf or lip 23 which is struck outwardly from the corresponding depending end flange 15 of the shelf 10 so as to form a horizontal extension of the top of the shelf and each leaf 23 is elongated in a direction transverse of the shelf. Each of these leaves 23 is composed of a pair of alining arms which extend horizontally so as to form a continuation of the top of the shelf and then are bent sharply vertically upward as best shown in Fig. 3 and have their outer ends connected by a cross bar 24. An important feature of the invention resides in the provision of an aperture 25 in each of these leaves or lips 23. Each of these apertures 25 is circumscribed by the arms of the hinge leaf, its cross bar 24 and the end edge of the shelf 10 and extends through the bend between the horizontal and vertical parts of the leaf or lip in which it is provided and is preferably of generally rectangular form with the opposite edges thereof parallel with one another. Each aperture 25 is also elongated in a direction transverse of the shelf.

In register with each of the leaves or lips 23, the wall of the corresponding side bracket 11 is provided with a cruciform or T-shaped slot or aperture 26. Each of these T-shaped slots 26 comprises a central vertical part 27 which is generally of rectangular form and of a width approximately equal to the corresponding dimension of the aperture 25 in the companion hinge leaf 23. At its upper end each T-shaped slot 26 has two horizontally extending branch extensions or slots 28, 28 the distance from one end of these branches 28 to the opposite end thereof being approximately equal to the total width, transversely of the shelf 10, of the companion hinge leaf or lip 23 and the height of these branches 28 being approximately equal to the thickness of the companion leaf 23. Each of the T-shaped slots 26 also preferably has an upward extension 29, this upward extension being preferably of the same width as the lower vertical part 27 of the slot and this upward extension 29 also being of a height approximately equal to the thickness of the metal of which the shelf and bracket are made.

Each T-shaped slot 26 is adapted to be partly filled by a tang 30 which is formed integrally and is coplanar with the side wall of the corresponding end bracket 11. This tang is joined to the body of the bracket along the lower part of the vertical part 27 of the T-shaped slot and extends upwardly into the upward projection 29 of the T-shaped slot, as best shown in Fig. 7. It will be seen that, with the tang 30, the portion 27 of the aperture 26 is of inverted U-shaped form and that the slots 28 extend laterally outwardly from each side of this inverted U-shaped portion 27 of the aperture 26 below but adjacent the upper end of this aperture. Before assembly, this tang is bent outwardly from its bracket 11 at an angle as best shown in Figs. 4 and 6.

In this angular position of the tang 30 it will be seen that the pair of lips or hinge leaves 23 at one end of this shelf 10 can be slipped through the pair of T-shaped slots 26 in the corresponding end bracket 11. Thus, by bringing this end bracket 11 generally into parallelism with the shelf 10, the laterally bent end extremities 24 of the pair of lips or hinge leaves 23 can be slipped into the lateral extensions 28 of the two T-shaped slots 26. Upon then swinging the end bracket 11 to a vertical position the lips or hinge leaves 23 are threaded through the slots so that the horizontal body parts thereof are disposed in these lateral extensions 28 thereof. The parts then occupy the position shown in Fig. 6. In this position the vertically bent extremities 24 of the lips or hinge leaves 23 are disposed against the outer face of the corresponding end bracket 11 and the apertures 25 thereof are in vertical alinement with the lower vertical parts 27 of the two T-shaped slots 26.

In order to retain the lips or hinge leaves 23 against removal from the T-shaped slots 26, each of the pair of tangs 30 is now bent back into parallelism with the body of the end bracket 11 from which they were formed. In so doing, as best shown in Figs. 5 and 7, it will be seen that the tangs 30 enter the apertures 25 of the lips or hinge leaves 23. Accordingly in this position of the tangs 30 it will be seen that the lips or hinge leaves 23 cannot be removed from the T-shaped slots 26 because the ends of the tangs 30 prevent such removal and only permit such swinging movement as is sufficient to permit each bracket 11 to be swung from the vertical position shown in Fig. 7 to the horizontal position shown in Fig. 8, the bracket in this latter position lying flat against the upper surface of the shelf 10 so that the shelf, with its two brackets 11, can be conveniently shipped or stored. It will therefore be seen that the two brackets 11 for each shelf 10 are permanently hinged thereto so that there is no danger of losing any of these three parts in transit or in storage.

From the foregoing it will be seen that the present invention provides shelf and end bracket units for library bookstacks in which each bracket is hinged to the shelf in such manner that it can be folded flat against the shelf for storage or transit and in which each bracket is permanently hinged to the shelf by a simple hinge connection which adds no substantial expense to the cost of the unit and which is strong and operates without danger of binding. It will particularly be noted that the two parts of the hinge are provided without adding any metal to either the shelf or its end brackets, the parts of the hinge being merely stamped out of the existing metal. Further, the parts of the hinge can be formed and assembled without the use of special tools or any complicated manipulative procedure.

I claim as my invention:

1. In a shelf unit for library book stacks having a generally rectangular sheet metal shelf and a perpendicular sheet metal end bracket disposed against one end of said shelf, the combination therewith of a permanently locked hinge connecting said end bracket with said shelf and permitting said end bracket to be swung downwardly on top of said shelf, comprising a hinge leaf projecting from said one end of said shelf, said hinge leaf having a pair of horizontally outwardly and then vertically upwardly turned arms spaced transversely of said shelf and in alinement with each other and a cross bar rigidly

connecting and forming a coplanar continuation of the outer vertically turned ends of said arms thereby to provide an aperture in said hinge leaf circumscribed by said arms, said one end of said shelf and said cross bar, said bracket being provided with spaced horizontal slots through which said arms severally project and having a coplanar portion of its body disposed between said slots and extending in the upright position of said end bracket upwardly into said aperture in said hinge leaf to prevent withdrawal of said hinge leaf from said slots.

2. In a shelf unit for library book stacks having a generally rectangular sheet metal shelf including a transverse depending flange at at least one end thereof, and a sheet metal end bracket adapted to be vertically disposed against the outer face of said flange and having its upper portion rising above said shelf, the combination therewith of a permanently locked hinge connecting said end bracket with said shelf and permitting said end bracket to be swung downwardly against the top face thereof, comprising an integral hinge leaf formed from the metal comprising said flange and projecting from said one end of said shelf, said hinge leaf having a pair of horizontally outwardly and then vertically upwardly turned arms spaced transversely of said shelf and in alinement with each other and a

cross bar integral with and connecting and forming a coplanar continuation of the outer vertically turned ends of said arms thereby to provide an aperture in said hinge leaf circumscribed by said arms, said one end of said shelf and said cross bar, said bracket being provided with an aperture having an inverted U-shaped portion defining an upstanding tank coplanar and integral with said bracket and also having a slot 10 extending laterally outwardly from each side of said inverted U-shaped portion below but adjacent the upper end of said U-shaped portion, said arms of said hinge leaf projecting through said laterally extending slots and said tang projecting through said aperture in said hinge leaf to prevent separation of said shelf and bracket.
